US00D543189S

(12) **United States Design Patent** (10) **Patent No.:** **US D543,189 S**
Jung et al. (45) **Date of Patent:** **** May 22, 2007**

(54) **MOBILE PHONE**

(75) Inventors: **Yun-Bin Jung**, Seoul (KR); **Ki-Sung Kim**, Seoul (KR); **Yoon-Young Cho**, Seoul (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/254,686**

(22) Filed: **Feb. 28, 2006**

(30) **Foreign Application Priority Data**

Dec. 22, 2005 (KR) 30-2005-0043549

(51) **LOC (8) Cl.** **14-03**

(52) **U.S. Cl.** **D14/138**

(58) **Field of Classification Search** D14/137, D14/138, 147, 218, 341-347; 455/90.3, 556.1, 455/556.2, 575.1, 575.3, 575.4; 379/433.01-133.13; 361/814; 348/14.02

See application file for complete search history.
